CLAIM

The ornamental design for a target for a bag toss game as shown and described.

DESCRIPTION

FIG. 1 is a perspective view of a target for a bag toss game showing my design.

FIG. 2 is a front view of the design.

FIG. 3 is a rear view of the design.

FIG. 4 is a right side view of the design.

FIG. 5 is a left side view of the design.

FIG. 6 is a top view of the design; and,

FIG. 7 is a bottom view of the design.

The broken lines in FIG. 3 illustrate features that form no part of the claimed design.
